UNITED STATES PATENT OFFICE.

JOHN PETER WENNERSTEN, OF CHICAGO, ILLINOIS, ASSIGNOR OF TWO-
THIRDS TO AUGUST JOHNSON AND J. AUGUST JOHANSON, BOTH OF
SAME PLACE.

HORSESHOE-NAIL-FINISHING MACHINE.

SPECIFICATION forming part of Letters Patent No. 358,904, dated March 8, 1887.

Application filed June 26, 1886. Serial No. 206,360. (No model.)

To all whom it may concern:

Be it known that I, JOHN PETER WENNERSTEN, a citizen of Sweden, residing at Chicago, in the county of Cook and State of Illinois, have invented a certain new and useful Improvement in Horseshoe - Nail - Finishing Machines, of which the following is a full, clear, concise, and exact description, reference being had to the accompanying drawings, forming a part of this specification.

My invention relates to improvements in that class of horseshoe-nail-finishing machines in which the principal operative mechanism consists of a series of rolls in the surface of which is imprinted the form of the nail to be finished. These rolls, acting in pairs, receive the blank or rough nail and reduce it to the finished product.

My object is to improve this machine in some minor details, but principally to perfect that part in which the surplus metal is cut off and in which the point is formed.

In the drawings illustrative of my invention, Figure 1 is a front elevation. Fig. 2 is a section on line x x of Fig. 1. Fig. 3 is a detailed plan view of the intermittent-feeding device. Fig. 4 is a rear end elevation. Fig. 5 is a section on line Y Y of Fig. 8. Fig. 6 is a section on line Z Z . Fig. 7 is a plan view of the cutting-off and pointing roll. Fig. 8 is a plan view of the upper rolls. Fig. 9 is a section of the channel-piece H. Fig. 10 is a view of the finished nail and of the cut off refuse.

Similar letters refer to similar parts throughout the various views.

The frame A is provided with standards a and a' , fitted with adjustable brasses to receive the several shafts B B B, journaled therein. These shafts are geared in pairs by the pinions b b b , and have a fixed rotative relation to each other through the gears b' b' b' . The train is actuated by the large gear b^2 , which in turn is given motion through the pinion b^3 by the driving-pulley b^4 .

On the rear ends of the upper pair of shafts B and B as shown in Figs. 4 and 5, are carried the roughing-rolls C and C', respectively. On the ends of the middle pair of shafts B and B are carried the finishing-rolls D and D', re-

spectively. On the ends of the lower pair of shafts B and B are carried the pointing-rolls E and E', respectively, all these rolls being of hardened steel.

Above the center of the upper rolls, C and C', at the point at which they are tangent, is the feeding-tube F. This tube is of sufficient length to receive several blanks one above the other, the blanks being of the form usual to this class of nails.

A finger, f, as shown in Fig. 3, is pivoted at f' , and carries the projecting point f'' , having a motion within and through the slot at the bottom of the feed-tube F. A retaining-spring, f^3 , serves to hold this point in position to prevent the feeding of the blanks except at regular intervals, which are determined by the pins carried by the collar B' on the shaft B. This collar is provided with a set-screw to permit of accurate regulation of the time of dropping the blanks into the rolls below. These blanks are received by the rolls C and C' while they are in the position as indicated by Fig. 5, and by their continued rotation the blank is swaged into the form of the die in their surface, the surplus metal serving to elongate the blank. From these rolls the rough nail passes through the channel of the guide-piece G to the second pair of rolls, D and D', being received by them while in the position indicated. These relative positions, it will be understood, are determined by the length of nail operated upon. Here the rough nail is finished with regard to its head and to the body. Surplus metal is cut off by the shearing action of the knife-edge d, acting against the surface of the roll D'. Thence the unpointed nail passes into the channel-piece H. (Shown in enlarged section in Fig. 9.) Finger-springs h are inserted in this channel to guide accurately the nail into the recesses of the pointing-rolls below, into which the nail next passes. An enlarged view of these rolls is shown in Figs. 6 and 7, they being represented in the position at the time at which the nail is received. By the continued rotation of the rolls the nail is seized between the points of the spring e' of the roll E' and the spring e of the roll E. Further rotation

95

while the nail is in this secured position brings its end over the die-opening e^2 of the roll E, into which it is forced by the eccentric V-faced punch e^3 . The shearing action of this punch 5 against the die-edge of the opening e^2 cuts off the surplus metal and leaves the pointed finished nail, as shown in Fig. 10.

The roll E' is recessed at r to allow the cut off waste S to lie within its circle until the 10 rolls are turned sufficiently to free it, when it is forced from the V-shaped punch by the spring e^4 and falls down. The nail has already dropped from the rolls, the point on which it rested, e^5 , being of such incline as to permit it 15 to do so freely when it is forced from its bed by the spring e .

For convenience of construction and for other reasons the roll E is formed of two plates or parts, as represented, keyed together by the 20 pins $p\ p$. The cutting-edges of the die can consequently be readily sharpened, and, by allowing space between the two parts of the roll when first made, wear can be taken up by bringing the two elements closer together. The roll 25 E, for similar reasons, is constructed in three parts, keyed together by pins $p'\ p'$. The middle element, E^2 , need alone be of hardened steel, and the springs, if desired, can be secured to the other elements. The middle piece, 30 being alone subject to strains, can thus be cheaply replaced in case of breaking. It is ordinarily of great difficulty in mechanism of this class to have the parts subject to strain "stand." It is consequently all-important to 35 construct them so as to be easily and quickly replaced. I have described these rolls throughout as though constructed to produce but one nail at each revolution. They may be provided with as many die forms as desired. Those 40 represented in the drawings have two sets of die forms in their surface, and consequently will produce two nails at each revolution. This number may be increased as is found desirable. As illustrated and described, the forming 45 of the nail is divided into two operations—that of roughing and that of finishing. These may be abridged and one pair of rolls perform both operations; but the preferable method is by the use of two pairs of rolls, as described. 50 Each nail-machine is provided with several sets of rolls, to allow of the production of different lengths and shapes of nails. It is obvi-

ous that many equivalent devices can be used in the rolls E and E'. Coil-springs, with suitable attachments, can be substituted for the flat springs. The pins $p\ p$ may be dispensed with. It is also unnecessary to construct the rolls in parts, although desirable. To prevent the springing of these rolls C and C', D and D', E and E' one from the other by the pressure of 55 the nail, the shafts B B B are produced beyond the rolls and wearing-collars placed thereon, against which shoes or bearing-pieces I I I are held and adjusted by the set-screws $i\ i\ i$, threaded in the flanges $a^2\ a^2$ of the main frame 60 of the machine.

Having described my invention, what I claim as new, and desire to secure by Letters Patent, is—

1. In a horseshoe-nail machine, the combination of a pair of rolls, E E', geared to revolve together and toward each other above their axes, a V-shaped die-opening and a recess in one roll and a punch corresponding with said die-opening and a recess in the other 75 roll, a spring, e , in the recess of the roll E and a spring, e' , in the recess of the roll E', substantially as and for the purpose set forth. 80

2. In a horseshoe-nail machine, the tube F, the feeding-finger f , the forming-rolls C and C' D and D', the pointing-rolls E and E', and the channel-pieces G and H, in combination with the shafts B B B and pinions $b\ b\ b$, and suitable driving mechanism, substantially as herein set forth. 85

3. In a horseshoe-nail machine, the combination, with the pairs of rolls D D' and E E', of a channel-piece, H, placed between the said pairs of rolls to convey the nail from one pair to the other, and converging spring-fingers $h\ h$, secured within the channel-piece, substantially as and for the purpose set forth. 90

4. In a horseshoe-nail machine, the combination of bearing-collars on the ends of the shafts B B B with the shoes I I I, adjusted by 95 the set screws $i\ i\ i$, engaged in the flange-pieces $a^2\ a^2$, substantially as and for the purpose described.

In witness whereof I hereunto subscribe my name this 22d day of June, 1886.

JOHN PETER WENNERSTEN.
